BOILER DRUM

Isaac Harter, New York, N. Y., assignor to The Babcock & Wilcox Company, Bayonne, N. J., a Corporation of New Jersey

Application March 12, 1927, Serial No. 174,887
Renewed September 29, 1931

7 Claims. (Cl. 220—25)

5 My invention relates to seamless drums for high pressure boilers and the like having man-hole covers, usually approximately circular, for internally closing a manhole opening or the like, smaller than the cover, and relates further to methods of making the covers. The invention to be set forth covers a modification of the structure and methods disclosed in my copending application filed September 9, 1926, Serial No. 10 134,513.

15 Various suggestive embodiments of my present invention are illustrated in the accompanying drawings in which Figure 1 is a longitudinal section through the end of a seamless drum closed by the cover of my invention; Fig. 2 is a plan view of the cover; Fig. 3 is a side view of the cover; Figs. 4 and 5 are plan and side views, respectively, of a modification; Figs. 6 and 7 are plan and side views, respectively, of another modification; 20 and Figs. 8 and 9 are plan and side views, respectively, of a third modification.

25 Like reference characters indicate like parts in the several views.

The drum A may be made as shown in my 30 earlier application, above referred to, by heating and turning in or closing in the ends of a seamless shell, while hot, to form the relatively small circular manhole opening 10 serving as its largest opening. The methods disclosed in my earlier 35 application do not work well with short drums. The covers get hot when placed inside a short drum before forming the reduced ends and may be damaged or distorted so as not to seal tightly against the seat or ledge 11 around the opening 40 10. In the embodiment shown in Figs. 1 to 3, therefore, I make the metal cover B in two parts 12, each small enough to enter the manhole 10 in the drum. These parts can be readily assembled 45 within the drum and then fabricated, as by being welded, into an integral unit after the drum is otherwise completed.

50 As shown in Figs. 2 and 3, these parts are identical halves meeting in a central diametral plane. They may be of cast or forged metal and require no machine finishing except possibly on a face 55 13 of a flange 14 which bears against the ledge 11 surrounding the manhole 10, to provide an accurate fit between this face and the seat. It 50 may be also desirable to machine the abutting faces 16 of the parts 12. Cored or drilled bolt holes 17 extend through each portion 12 and end in sockets 18, large enough to hold the head of the bolt 19 or its nut 20. Dowel pins 22 fit 55 closely in holes 23 to positively align the portions

12 to insure a register of the parts of the face 13 and of the machined surfaces 16.

The diametral face 16, of each portion, ends at its longer edges in surfaces 25 and 26, each set back and sloping away from the face 16. This 60 gives, when the cover is assembled, an effect of diametrically disposed and relatively deep wedge-shaped slots 27 and 28 on opposite faces of the cover B. These slots are later filled with metal electrically deposited, thermit metal, or any suitable 65 welding substance. The parts are thus welded within the drum A to form the integral cover B. Any suitable method of welding may be used to make the covers integral.

70 Standing bolts 30 extend from the exterior face of the cover to retain the cover in place in the manhole with the ledge 11 pressing against any suitable gasket to make a tight joint that will withstand the steam pressure from within the drum. The bolts 30 secure the cover to the usual 75 bars or cross pieces 31 spanning or bridging the manhole 10 to rest at their ends on the drum A. A hinge section 32 is bolted to the interior face 80 of the cover B and retained by links 34 and 35 to a hinge section 36 bolted to the drum interior.

In Figs. 4 and 5 the two parts 37 of the cover C are much the same as B. A flat plate 38 just 85 small enough to enter the manhole 10 is bolted rigidly to the outside face of the cover after the parts are joined within the drum. The dowel pins 22 aligning the parts maintain the cover in shape during the assembly and the later filling of the slot 27 with a welding substance. One face 90 of the cover C is beveled or slotted as at 27 to permit welding of the two parts into an integral cover.

In Figs. 6 and 7 the two parts 40 and 41 of the cover D are not alike. The central plane surface 42 of part 41 ends in a rib or flange 43 which 95 fits in a corresponding or complementary recess 44 in the part 40. The parts of the cover are joined and brought into registry by dowels 22. The cover is bolted into a rigid unit by bolts passing through the flange 43 and entering the part 100 40. The cover is completed by filling the slot 27 in the inner face of the cover D with a welding substance.

In Figs. 8 and 9 the cover E is composed of two 105 unlike parts 46 and 47. The part 47 has a dove-tail rib 48 fitting slidably into a complementary slot in the part 46. Diametral slots 50 and 51, similar to those in cover B, are formed in the inner and outer faces, respectively, of the cover E to permit a welding of the parts 46 and 47 into 110 a unitary cover. A set screw 53 locks the parts

in proper registry. The welding operation completes the cover filling the opposed slots 50 and 51 with metal or other welding material.

It will be noted that, in the case of each variation or modification, the bolts and dowels are protected from the hot welding operation. In every cover the welding slots are not made so deep as to be dangerously near the fastening means; that is, the meeting surfaces of the parts of each cover are of such extent that the heat cannot reach the bolts and dowels and thus spoil the cover by warping them and the cover out of shape.

It will be apparent that the use of this cover and method of construction is not limited to seamless drums but is applicable wherever an integral cover is placed within a hollow body to fit an opening smaller than the cover. Any combination or arrangement of fastening means may be used as desired.

20 I claim:

1. A cover for fitting an opening in a drum from within the drum and comprising a plurality of component parts having contacting faces, dowel pins disposed in holes in said faces, said parts being welded together to form an integral cover, and means for attaching the cover to a drum.

25 2. In combination, a forged metallic high-pressure drum having therein a substantially circular hole surrounded by a seat facing the interior of the drum, and a substantially circular unitary cover disposed on the inside of the drum and adapted to fit said seat, said cover consisting of a plurality of component parts each of which is small enough to pass freely through said hole and said component parts having been passed through said hole into said drum and there fabricated into a unitary operative cover.

30 3. In combination, a forged metallic high-pressure drum having therein a substantially circular hole surrounded by a seat facing the interior of the drum, and a substantially circular unitary cover disposed on the inside of the drum and adapted to fit said seat, said cover consisting of a plurality of component parts each of which is small enough to pass freely through said hole and said component parts having been passed through said hole into said drum and there welded into a unitary operative cover.

35 4. In combination, a forged metallic high-pressure drum having therein a substantially circular hole surrounded by a seat facing the interior of the drum, and a substantially circular unitary

cover disposed on the inside of the drum and adapted to fit said seat, said cover consisting of a plurality of component parts each of which is small enough to pass freely through said hole, said component parts having been passed through said hole into said drum and there fabricated into a unitary operative cover, and said parts having thereon means for positively aligning them to insure an accurate registry of the cover with said seat.

80 5. In combination, a forged metallic high-pressure drum having therein a substantially circular hole surrounded by a seat facing the interior of the drum, a substantially circular unitary cover disposed on the inside of the drum and adapted to fit said seat, said cover consisting of a plurality of component parts each of which is small enough to pass freely through said hole and said component parts having been passed through said hole into said drum and there fabricated into a unitary operative cover, and means for holding said cover on said seat.

90 6. In combination, a forged metallic high-pressure drum having therein a substantially circular hole surrounded by a seat facing the interior of the drum, a substantially circular unitary cover disposed on the inside of the drum and adapted to fit said seat, said cover consisting of a plurality of component parts each of which is small enough to pass freely through said hole, said component parts having been passed through said hole into said drum and there fabricated into a unitary operative cover and said parts having thereon means for positively aligning them to insure an accurate registry of the cover with said seat, and means for holding said cover on said seat.

95 7. In combination, a forged metallic high-pressure drum having therein a substantially circular hole surrounded by a seat facing the interior of the drum, a substantially circular unitary cover disposed on the inside of the drum and adapted to fit said seat, said cover consisting of a plurality of component parts each of which is small enough to pass freely through said hole, said component parts having been passed through said hole into said drum and there welded into a unitary operative cover and said parts having thereon means for positively aligning them to insure an accurate registry of the cover with said seat, and means for holding said cover on said seat.

100 ISAAC HARTER.
